UNITED STATES PATENT OFFICE.

FRITZ WINKLER, OF LUDWIGSHAFEN-ON-THE-RHINE, GERMANY, ASSIGNOR TO
BADISCHE ANILIN- & SODA-FABRIK, OF LUDWIGSHAFEN-ON-THE-RHINE, GER-
MANY, A CORPORATION OF GERMANY.

MANUFACTURING ACTIVE CARBON.

Application filed September 29, 1923. Serial No. 665,627.

To all whom it may concern:

Be it known that I, FRITZ WINKLER, citizen
of the German Empire, residing at Lud-
wigshafen-on-the-Rhine, Germany, have in-
5 vented new and useful Improvements in
Manufacturing Active Carbon, of which the
following is a specification.

My invention relates to a process enabling
active carbon to be manufactured in an ordi-
10 nary shaft furnace, thus avoiding the use
of retorts heated from the outside, or of com-
plicated revolving furnaces.

According to my invention a highly active
15 carbon is obtained by applying direct heat,
in a shaft furnace, to coal or other carbona-
ceous material serving for the production of
the active carbon, which may be coal, lignite,
peat, earthy brown coal or wood or
20 other material, whether or not prepared
with alkalies or suitable salts and the like.
This material in the form of a powder or in
fine pieces is placed in the shaft furnace and
hot combustion gases are introduced from
25 below with sufficient pressure to make an
agitation or a whirling motion of the coal
or carbonaceous material within the said
furnace. The material is thus thoroughly
mixed and the whole mass is uniformly
30 heated. Further the intimate contact with
the hot fire gases causes the heating to take
place very quickly; and a particularly effi-
cient utilization of the heat can be obtained
by using the gases issuing from the furnace
35 for drying and preheating the material to be
subjected to the activating treatment. The
fire gases may also have an admixture of
steam either continuously or periodically.
The activated carbon can be readily with-
40 drawn from the furnace by blowing it out
from an opening near the bottom of the
same by means of the fire gases.

In order to further illustrate the manner
of carrying my invention into effect, I will
45 describe it with reference to the accompany-
ing diagrammatic drawing, but the inven-
tion is in no way restricted to this example.
Figure 1 represents a vertical section of a
furnace embodying this invention.

A represents a combustion chamber in
50 which fire gases are produced by burning
fuel with air forced into the said chamber;
preferably blue gas and air are used which
are blown into the said chamber by means

of blower H in a tangential direction to
make the combustion complete. The com-
bustion gases then pass into a cylindrical
shaft furnace B which is separated from the
combustion chamber A by a plate of fire-
clay, perforated with small apertures of
say 5 millimetres width and carrying a layer
55 of G of about 4 centimetres thickness of pieces
of fireclay of hazelnut size. The furnace B,
at its lower part, is conically reduced in size.
The coal, for example peat charcoal, which
is in grains of about 3 millimetres size is
60 placed on the layer of the fireclay in a layer
of about 40 centimetres in thickness. The
fire gases are blown through this layer with
a pressure of about 150 millimetres of water
giving the peat coke on their passage a
65 whirling movement. The coke is thus heat-
ed very rapidly and after a few minutes is
uniformly red-hot. When the temperature
has reached about 800 degrees centigrade,
steam is blown into the said combus-
70 tion chamber A to mix there with the fire gases
and the mixture is then allowed to act on
the coke for about 10 minutes. The flue
gases pass through the pipe J into the cham-
ber E where fresh fuel is stored on a suit-
75 able support L, for example a tipping grate,
and after having preheated said charge of
fuel they leave through waste pipe F. The
material in furnace B after sufficient treat-
80 ment is blown out through a discharge C
into a chamber D, which chamber may be
filled with an inert gas. This may be done
by closing a waste pipe F and opening the
discharge C which is connected by a pipe C₁
85 with a storage chamber D, from which the
air has been removed and replaced by nitro-
gen or carbon dioxide or other inert gas.
When the furnace B is operated, the pipe C
is closed by the stopper shown. By the
90 closing of the waste pipe F the gases are
compelled to escape through the said dis-
charge C carrying along the active carbon
that is ready into the chamber D where it is
cooled. After opening the waste pipe F and
95 closing the discharge opening C a fresh
charge of peat coke is filled in from the
chamber E and the furnace is ready for a
further operation. In the chamber E a sup-
100 ply of peat charcoal or other like material
to be treated is kept and treated with the
flue gas being dried and preheated thereby.
105

The trap K is only opened when a fresh supply of fuel is charged into the furnace B.

It will be clear that no special means are necessary to prevent particles being blown right through C as in the chamber D the speed of the gases is reduced and the particles are allowed to settle.

The active carbon thus obtained is exceedingly active and may be used for example 10 for purifying gases from sulfuretted hydrogen by catalytic oxidation with air with very good result.

Instead of peat charcoal other carbonaceous or coal material such as for example 15 anthracite, lignite, lignite charcoal, or wood impregnated with potash or zinc chlorid or other salts, may be used and treated in the same manner yielding excellent results.

I claim:

20 1. The process of manufacturing active carbon which consists in treating carbonaceous material in a shaft furnace with hot combustion gases which are blown through the said material with sufficient pressure to establish a strong agitation of the material.

25 2. The process of manufacturing active carbon which consists in treating carbonaceous material impregnated with a salt promoting activation of coal in a shaft furnace

30 with hot combustion gases which are blown through the said material with sufficient

pressure to establish a strong agitation of the material.

3. The process of manufacturing active carbon which consists in treating lignite material in a shaft furnace with hot combustion gases which are blown through the said material with sufficient pressure to establish a strong agitation of the material. 35

4. The process of manufacturing active carbon which consists in treating lignite coke in a shaft furnace with hot combustion gases which are blown through the said material with sufficient pressure to establish a strong agitation of the material. 40

5. The process of manufacturing active carbon which consists in treating lignite coke in a shaft furnace with hot combustion gases and steam which are blown through the said material with sufficient pressure to 45 establish a strong agitation of the material. 50

6. The process of manufacturing active carbon which consists in treating lignite coke in a shaft furnace with hot combustion gases first alone then with an admixture of 55 steam, which are blown through the said material with sufficient pressure to establish a strong agitation of the material.

In testimony whereof I have hereunto set my hand.

FRITZ WINKLER.
